DESIGN FOR A DRESS

Jane Walker, New York, N. Y.

Application November 20, 1946, Serial No. 134,916

Term of patent 3½ years

(Cl. D3—26)

To all whom it may concern:

Be it known that I, Jane Walker, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

The characteristic feature of my design resides in the combination on the fly front dress disclosed, of the specific double flapped pocket on the skirt as shown.

I claim:

The ornamental design for a dress, substantially as shown and described.

JANE WALKER.
